United States Patent Office.

A. C. VAUGHAN, OF PHILADELPHIA, PENNSYLVANIA.

Letters Patent No. 76,278, dated March 31, 1868.

IMPROVEMENT IN AUGERS.

The Schedule referred to in these Letters Patent and making part of the same.

TO ALL WHOM IT MAY CONCERN:

Be it known that I, A. C. VAUGHAN, of Philadelphia, Pennsylvania, have invented an Improved Auger; and I do hereby declare the following to be a full, clear, and exact description of the same.

My invention consists of a tube with a screw-thread on the outside, and cutting-edges at the lower end, arranged in respect to the screw-thread, as fully described hereafter, so that the said thread will guide the tool as it penetrates a block or strip of wood, and so that, whatever may be the extent to which the tool is worn, cutting-edges properly arranged may be produced, by cutting away the screw-thread, and the tube adjacent to the same.

In order to enable others skilled in the art to make and use my invention, I will now proceed to describe its construction and operation, reference being had to the accompanying drawing, which forms a part of this specification, and in which—

Figure 1 is an exterior view of my improved auger.

Figure 2, a sectional view on the line 1-2, fig. 1.

Figure 3, an inverted plan view of fig. 1; and

Figure 4, a detached sectional view, drawn to an enlarged scale.

A is a metal tube, near the upper end of which is a flange, a, the said tube being enlarged in diameter internally, from a point, c, upward, for a purpose described hereafter.

At the lower end of the tube is a recess, y, and on the outside is a screw-thread, b, which meets the lower edge of the tube at one side of the recess y, where a lip, e, is formed. The thread b is cut away at its lower end, so as to form two cutting-edges, i i¹, the former being vertical, and the latter slightly inclined from the point where it meets the edge i, to the lip e, (fig. 1,) the curved portion of which is also formed into a short cutting-edge, bevelled from the inside. The auger is secured to a brace, and is operated in the same manner as an auger of the ordinary construction, a portion of the wood being received within the tube, while the particles or chips detached by the action of the cutting-edges are withdrawn by the screw-thread b.

Although this tool may be employed as a substitute for the ordinary auger, it is especially adapted for removing spikes from planks and beams, into which they have been driven. To effect this object, the end of the tool is placed against the wood, directly over the spike, which, as the opening is bored, is received into the hollow stem. When the auger has penetrated a distance equal to the length of the spike, it is withdrawn, the spike, and a portion of the wood surrounding it, remaining within the auger, from which they may be readily removed, inasmuch as the body of wood surrounding the spike has been so reduced in passing through the contracted end of the tube below the shoulder e, that it fits but loosely in the enlarged part of the tube above the shoulder.

It will be seen that, as the outer edge of the screw-thread b is on a line with or nearly on a line with the cutting-edge i, the said thread, as an opening is bored, will bear against the sides of the said opening, and will thus guide the tool, so that it cannot change its direction after it has entered the wood, and that whatever may be the extent to which the tool is worn, cutting-edges properly arranged, may always be produced, by cutting away a portion of the thread, and of the tube adjacent to the same.

I do not claim, broadly, a tubular auger, with an external screw-thread, nor the arrangement, in such an auger, of an inner cutting-edge, outer cutting-edge, and a recess, y; but

I claim as my invention, and desire to secure by Letters Patent—

The metal tube A, with its external screw-thread, b, extending to the lower end of the tube, when the latter, with the screw-thread, is cut away, to form the cutting-edges i i¹ i², and when the outer edge of the screw-thread is on a line with or nearly on a line with the outer cutting-edge i, for the purpose described.

In testimony whereof, I have signed my name to this specification in the presence of two subscribing witnesses.

A. C. VAUGHAN.

Witnesses:

EDW. H. WILLIAMSON,

WM. ALBERT STEEL.
